UNITED STATES PATENT OFFICE

PAUL Y. DUFFEE, OF SPRINGFIELD, OHIO, ASSIGNOR TO THE OHIO STEEL FOUNDRY COMPANY, OF LIMA, OHIO, A CORPORATION OF OHIO

RETURN HEADER

Application filed January 27, 1930. Serial No. 423,808.

This invention relates to improvements in returns headers for high pressure pipe lines, and more particularly to an assembly including a U-fitting for connecting the ends of pipes or tubes such as used in high-pressure stills and cracking units in oil refining installations and the like.

The object of the invention is to provide a header which will permit of ready removal of the U-fitting to afford access to the tubes for cleaning, and when assembled, to offer a pressure tight connection and a smooth stream line flow between the tube ends.

A preferred embodiment of my invention is disclosed in the accompanying drawings in which

Figure 1 is a view in longitudinal section through a return header employing the improved assembly.

Figure 2 is a view in transverse section through the header as taken on line 2-2 of Figure 1.

Figure 3 is a top plan view of the assembly.

Figure 4 is a bottom view of one of the locking sleeves removed, and

Figure 5 is a bottom view of one section of the header as taken on line 5-5 of Figure 2.

As shown in Figure 1, the return header assembly is mounted at the ends of two parallel tubes 1, 1 terminating in close proximity to each other. A base member 2, consisting of a pair of collars, 2a, 2a integrally joined by a web 2b, is fitted over the ends of the tubes a short distance below their extremities, the collars being of a slightly greater diameter than the tubes to insure a slightly loose fit and the distance between the centers of the collars being proportioned to the distance between the tubes so that once applied, the base member maintains the ends of the tubes in alignment.

Fixed to the ends of the tubes are nipple-like end fittings 3, 3 which are recessed to receive the tube ends, the passage throughout

their lower ends being increased in diameter by the thickness of the tube walls with an additional shallow groove 3a. The tube ends are fitted into these recesses and then rolled or expanded and finally welded as at 3b, thus making a permanent joint with smooth wall surfaces. These end fittings are manifestly fixed to the tube ends after the base member 2 has been slipped onto the ends of the tubes, the collar portions 2a of the base member being eventually drawn up tightly against the shoulders at the adjacent ends of the end fittings.

Straddling the outer ends of the end fittings is a U-fitting or bend 4 having a passage therethrough describing an arc of 180°. The ends of the U-fitting seat upon the outer ends of the end fittings 3, 3 which are tapered and rounded slightly as at 3c, while the ends of the U-fitting are recessed with an internal straight tapered or beveled seat 4a, thus forming a variation of the ball joint.

The ends of the U-fitting are held or clamped to their seats in leak-tight connection with the end fittings on the tubes by means of a pair of demountable sleeves 5, 5 having the form of a hollow cylindric casing extending axially with respect to the tubes and beyond the U-fitting 4. The lower portions 5a of these sleeves are circular in form and surround the tube ends while the upper portions 5b have sections cut away so that they are substantially semi-circular in cross-sections with their open sides facing inwardly and toward each other.

These sleeves 5, 5 are anchored to the base member 2 by a type of bayonet lock connection with the collars 2a, 2a, as will now be described. The base member is cast with circumferential grooves about the collars 2a, 2a, thereby forming integral flanges 2c, 2c at their upper and lower edges, and in the upper flanges are formed recesses 2d spaced apart at intervals of 90°. At the lower edges of the sleeves 5, 5 are complementary sets or

groups of inwardly projecting lugs 5c, 5c (Figure 4) which register with the recesses 2d in the flanges 2c of the base member 2. Thus by dropping each sleeve over the recessed flanges of the base member and turning them axially through 45°, the two parts are locked together, it being noted that the groove or channel separating the two flanges 2c, 2c of the collars 2a is slightly wider than that of the lugs 5c, so that the connection can be readily made without binding. These sleeves are anchored to the base member before the U-fitting is mounted in place, in order that they may be turned through the arcs necessary for completing the locking connections with their open sides facing inwardly and toward each other. At this point in the assembly the upper ends of the sleeves are open, so that the U-fitting can be easily dropped into place, whereupon the locking fixtures for said U-fitting are applied, as will now be described:

The upper edges of the sleeves 5, 5 which extend through an arc of slightly greater than 25 a semi-circle, as shown in Figure 3, are internally flanged to form downwardly facing shoulders 5d, 5d, and in the wall of each sleeve is an opening 5e located centrally of the upper edge and immediately below the 30 shoulder 5d.

Mounted at the upper ends of the sleeves 5, 5 are demountable locking fixtures 6, 6, which are held in place by the shoulders 5d and openings 5e. These fixtures have the 35 form of metal blocks or plates generally circular in shape and having a marginal flange 6a of the same arc and radius as the sleeve below the shoulder 5d, and a lug 6b projecting radially from the flange. The central 40 portion of each fixture tapers to a substantial thickness and mounted therein is a set screw 7. As shown in Figures 1 and 2, a fixture 6 is inserted or fitted into the upper end of each sleeve so that the lug 6b registers with 45 the opening 5e and the flanges engage beneath the shoulder 5d, this being accomplished by sliding the block into place from the inner open side of the sleeve. The set screw 7, 7 are turned up while the fixtures 5 are being 50 inserted in place and then turned down to bring their lower ends into contact with lugs 4c, 4c cast on the outer surface of the U-fitting in alignment with the center lines of the tubes 1, 1, the pressure of the set screws 55 against the U-fitting drawing all of the parts tightly together in leak-tight connection.

To remove the U-fitting 4, it is only necessary to loosen the set screws 7, 7, and remove the fixtures 6, whereupon the U-fitting can be lifted out, thus leaving a clear opening for introducing the cleaning tools into the open ends of the tubes.

Among the advantages of the return bend herein disclosed may be mentioned the simplicity of construction, the ease of assembly

and maintenance, the accessibility of the tubes for cleaning, the smooth stream line which reduces both erosion and corrosion in a considerable degree, and the ability to make the several parts of the metal or alloy best suited to render maximum service.

I claim as my invention:

1. A return header for connecting the ends of a pair of parallel tubes comprising a base member having collars through which the 75 ends of said tubes project, end fittings welded to the ends of said tubes, cylindric sleeves extending axially with respect to each tube and having locking connection at their lower ends with the collars of said base member, a U-fitting removably seating upon said end fittings with their contacting ends forming ball joints, and locking members removably mounted in the outer ends of said sleeves and 80 including set screws bearing against said U-fitting in axial alignment with said tubes.

2. A return header for connecting the ends of parallel tubes comprising a base member consisting of a pair of connected collars 90 through which the ends of said tubes project, end fittings having annular recesses into which the tube ends are inserted and welded and rounded outer ends, cylindric sleeves open at their ends and adapted to have detachable locking connections at their lower 95 ends with the collars of said base member, a U-fitting seating at its ends upon said end fittings, said sleeves having wall sections removed adjacent their outer ends and internal 100 marginal flanges, demountable locking fixtures having marginal bearing contact with said flanges and provided with set screws bearing against said U-fitting in axial alignment 105 with said tubes.

3. A return header for connecting the ends of parallel tubes comprising a base member consisting of connected collars adapted to be slipped over the ends of said tubes, end fittings permanently fixed to the ends of said tubes, sleeves having demountable connection with said collars and extending axially beyond said tube end fittings, a U-fitting adapted to connect said tubes with openings seating upon said end fittings, and locking 110 fixtures removably supported at the outer ends of said sleeves and adapted to exert pressure on said U-fitting axially of said tubes.

4. A return header for connecting the ends 115 of parallel tubes comprising end fittings adapted to be permanently fixed to the ends of said tubes, a casing enclosing said tube end fittings and the space there beyond, and having a separate base through which the 120 ends of said tubes are inserted before said end fittings are applied, and sleeve-like members having locking connection with said base, a U-fitting seating on said end fittings, and an adjustable pressure member mounted 125

at the outer ends of said sleeve-like members and bearing against said **U**-fitting.

5. A return header for connecting the ends of the parallel tubes comprising a pair of connected collars adapted to fit loosely over the ends of said tubes, and to abut against end fittings permanently fixed to the ends of said tubes, a **U**-fitting adapted to connect said tubes with its ends in bearing contact with said end fittings, a pair of sleeves having cylindric base portions adapted for locking connection with said collars, and locking members adapted to be mounted at the outer ends of said sleeves and bearing on said **U**-fitting.

10 15 Signed at Springfield, Ohio, this 17th day of January, 1930.

PAUL Y. DUFFEE.
